UNITED STATES PATENT OFFICE.

LAURENCE C. MARTIN, OF PROVIDENCE, RHODE ISLAND.

EYEGGLASS CONSTRUCTION.

1,201,223.

Specification of Letters Patent. Patented Oct. 10, 1916.

Application filed November 24, 1914. Serial No. 873,674.

To all whom it may concern:

Be it known that I, LAURENCE C. MARTIN, a citizen of the United States, and residing at Sabin and Aborn streets, Providence, in the county of Providence and State of Rhode Island, have invented a new and Improved Eyeglass Construction, of which the following specification is a full disclosure.

This invention relates to eyeglass construction.

One of the objects thereof is to provide a simple and practical device whereby an eyeglass lens is securely connected to another member of the glasses.

Another object is to provide a construction of the above type in which while the parts are rigidly and reliably held yet they are readily removed.

Other objects are to provide a device of the above type of inexpensive construction and attractive appearance and the portions of which may be quickly and conveniently assembled.

Other objects will be in part obvious from the annexed drawings and in part indicated in connection therewith by the following analysis of this invention.

This invention accordingly consists in the features of construction, combinations of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views of which:—

Figure 1 is a perspective view of a lens clamp, one portion being cut away in order to show the construction more clearly. Fig. 2 is a sectional elevation through a portion of a lens clamp and associated parts, the section being taken substantially in the plane of the lens and along the line A—A of Fig. 3. Fig. 3 is a sectional view taken along the line B—B of Fig. 2. Fig. 4 is a side elevation of the device shown in Fig. 1. Fig. 5 is a sectional elevation of a different form of lens clamp and associated parts, the section being taken substantially in the

plane of the lenses and along the line C—C of Fig. 6. Fig. 6 is a side elevation of the lens clamp appearing in Fig. 5.

Referring now to Fig. 2 of the drawings, there is shown at 1 a portion of an eyeglass lens the edge of which is embraced by the lens clamp 2. It may here be noted that the term "eyeglass" is used broadly throughout to comprehend any device adapted to mount lenses upon the face, and that the term "lens clamp" is also used in a broad sense as denoting any device adapted to be secured or to secure another member to an eyeglass lens. The lens clamp 2 comprises a strap 3 provided at each side with a lug or wing 4. The strap 3 is of such nature as to be adapted to be bent to some extent transversely of its length to fit exactly the curve of the lens to which it is secured. Rigidly connected with this strap is a hollow post 5 at the outer end of which is secured a rectangular sleeve or box 6 which receives the end of the bow-spring 8 by which the lenses of the eyeglasses are connected together. The end of the spring 8 is held in position by a screw 9 tapped within the post 5 and lying flush with the outer surface of the sleeve 6 as at 10.

It is to be understood that the construction immediately above described is merely illustrative of the various possible embodiments of the invention.

Recurring to Fig. 1 of the drawings, it is seen that the wings 4 are widest in the direction of the length of the strap 3 at the point adjacent the strap and narrow in a direction toward the body of the lens. It will also be seen that these wings, as indicated at 11 and 12, taper substantially to an edge in directions away from and lengthwise of the strap 3. This tapering of the wings 4, or reinforcement of their lower portions, is an important feature and is best indicated in Fig. 3 of the drawings, the additional metal being emphasized in this sectional view by dots as at 13. The wings 4 are preferably firmly connected one with another by the cross-pin 14 which is soldered to or integral with these parts. This cross-pin as shown in Fig. 2 of the drawings, fits within a recess 15 formed in the lens 1 and the entire device is rigidly held in position by the use of a suitable readily fusible cement, a portion of which is indicated at 16.

The use and action of this device may be

outlined as follows:—The clamp is secured in position, as above noted, preferably by a fusible cement which immediately hardens and will hold the parts together with extreme tenacity. If, however, a line of cleavage should develop in the cement, the entire lens would soon become loose. Due, however, to the reinforcement of the wings 4 at 13 the chance of outward bending of these parts is reduced to a minimum. It will also be noted that this result is accomplished without rendering the device unsightly or wasting metal. The pin 14, moreover, securely holds the inner surfaces of the wings 4 at a fixed distance apart and aids materially in rendering the joint secure, although either of these features are of independent value. If it is desired to remove the clamp, as in the case of a broken lens, the parts are warmed and at a moderate temperature they readily fall apart, permitting the substitution of a new lens.

Among the advantages of forming the lugs as above described, it may be noted that there is gained a line of junction between the side lugs and the strap which is relatively short in a direction circumferential of the lens as compared with certain forms of cemented lens clamp now in general use in which the lugs are coextensive with the strap, and thus the present clamp may be more readily adjusted to embrace and fit properly different thicknesses of lenses without a tendency to buckle the metal out of its plane or in-line the lugs toward one another.

In Figs. 5 and 6 of the drawings, there is shown a different form of clamp which, nevertheless, embodies many of the above features and advantages. In this form, the lens 17 is provided with a pair of recesses 18. The lens clamp 19 comprises a strap portion 20 provided at each end with a pair of wings 21 which are reinforced at 22, as indicated in Fig. 6 of the drawings. These wings taper down at their connecting point substantially to the outer surface of the strap 20, as indicated at 23, and also narrow in thickness at this point, as indicated at 24. By this construction the clamp may be bent in a direction transverse of its length substantially at its center in order to conform to and fit closely the edge of the lens. This form of clamp is provided with a pair of flat lugs 25 which are rigidly secured to or integral with both of the adjacent wings 21 and with the strap 20, thus rigidly connecting all of these members together. These lugs fit within the recesses 18, above referred to, and the entire device is cemented in position as described in connection with the construction first set forth. It will be noted that the flat lugs 25 formed rigid with the strap 20 and the side lugs constitute in effect stiffening webs on the inner surfaces of the side lugs, and, if de-

sired, instead of these inner webs or the reinforcing shown, stiffening webs or beads might be used on the outer surfaces of the side lugs or wings, as at 26, and many of the advantages of this invention attained. It may also be noted that certain of the advantages of this invention may be attained by stamping the side wings out of sheet metal into such form that, although the metal itself is of substantially uniform thickness, nevertheless the metal with the cement filling is of tapering thickness and the outer surfaces converge in a direction away from the strap and preferably in a direction parallel to the strap.

It will thus be seen that there is provided a device in which the several objects of this invention are achieved and which is well adapted to meet the hardest conditions of practical use.

As many changes might be made in the above construction, and as many apparently different embodiments might be made of this invention without departing from the scope thereof, it is intended that all features herein described or shown in the accompanying drawings shall be interpreted as illustrative and not in a limiting sense.

Having thus revealed this invention, I claim as new and desire to secure the following combinations of elements, or equivalents thereof, by Letters Patent of the United States:—

1. In eyeglass construction, in combination, a lens and a lens clamp comprising a strap portion and a pair of side lugs embracing said lens and cemented thereto, each of said lugs being thickened adjacent its junction with the strap and tapering in thickness in a direction away from the strap.

2. In eyeglass construction, in combination, a lens and a lens clamp comprising a strap portion and a pair of side lugs having substantially parallel inner surfaces embracing said lens and cemented thereto, each of said lugs being thickened adjacent its junction with the strap and tapering substantially to an edge in a direction away from the strap.

3. In eyeglass construction, in combination, a lens and a lens clamp comprising a strap portion and a pair of side lugs embracing said lens and cemented thereto, each of said side lugs being thickened adjacent its junction with the strap and tapering in thickness in a direction away from the strap and terminating short of the ends of the strap in a direction circumferential of the lens.

4. In eyeglass construction, in combination, a lens and a lens clamp comprising a strap portion and a pair of side lugs embracing said lens and cemented thereto, each of said lugs being thickened adjacent its junction with the strap and tapering in thick-

ness by a rounded outer surface extending substantially to the lens in directions both circumferential and radial thereof.

5. In eyeglass construction, in combination, a lens and a lens clamp comprising a strap portion and a pair of side lugs having substantially parallel inner surfaces embracing said lens and cemented thereto, each of said lugs being thickened adjacent its junction with the strap and tapering substantially to an edge in a direction away from the strap, and each of said lugs terminating short of the ends of the strap in a direction circumferential of the lens.

10 6. As a new article of manufacture, a lens mounting for eyeglass construction, comprising a strap portion and a pair of unperforated side lugs having substantially parallel inner surfaces adapted to embrace and be cemented to the lens, each of said lugs being of materially increased thickness adjacent its junction with the strap and tapering in thickness throughout its length.

15 7. As a new article of manufacture, a lens

mounting for eyeglass construction, comprising a strap portion and a pair of side lugs adapted to embrace and be cemented to the lens, each of said lugs being of materially increased thickness adjacent its junction with the strap and of gradually diminishing thickness in a direction away from the strap to its outer edge portion, and each of said lugs terminating short of the ends of the strap in a direction circumferential of the lens.

20 8. A spectacle or eyeglass mounting comprising a lens ear, having a thick base end and an outer face tapered from the base end toward the free end and toward the longitudinal edges, for the purpose set forth.

25 In witness whereof, I hereunto subscribe my name, as attested by the two subscribing witnesses.

LAURENCE C. MARTIN.
